UNITED STATES PATENT OFFICE.

ELWOOD B. AYRES AND HERMANN BOGATY, OF PHILADELPHIA, PENNSYLVANIA,
ASSIGNORS TO PROCTOR & SCHWARTZ, INCORPORATED, OF PHILADELPHIA, PENNSYLVANIA, A CORPORATION OF PENNSYLVANIA.

ROTARY DRIER.

Application filed July 18, 1922. Serial No. 575,851.

To all whom it may concern:

Be it known that we, ELWOOD B. AYRES and HERMANN BOGATY, citizens of the United States, residing in the city and county of Philadelphia, Pennsylvania, have invented certain Improvements in Rotary Driers, of which the following is a specification.

One object of our invention is to construct 10 a drier in which the articles to be dried are located on a rotary carrier within a chamber while heated air is circulated in the chamber.

A further object of the invention is to 15 construct a drier so that the articles can be fed automatically to the rotating carrier, and, when dried, can be discharged automatically therefrom.

The invention also relates to details of 20 construction, which will be fully described hereinafter.

In the accompanying drawings:

Fig. 1 is a longitudinal sectional view of 25 our improved drier;

Fig. 2 is a plan view;

Fig. 3 is a transverse sectional view; and

Fig. 4 is a perspective view of a berry basket.

The present machine is so designed that it 30 can be used in connection with a berry basket forming machine. The baskets come from the forming machine in a damp condition and must be thoroughly dried before they can be packed for shipment. It will be understood, however, that the machine can be 35 used for drying other articles without departing from the main features of the invention.

1 is the casing of the drier. This casing 40 encloses a drying chamber in which is a rotary carrier 2 supported by wheels 2^a. This carrier consists of two heads 3 connected by an annular series of L-shaped strips 4, forming pockets 5 for the articles to be dried.

45 The strips are separated so that air can circulate around the articles, which, in the present instance, are berry baskets made of wood bent into shape and fastened. These baskets are nested and each pocket is shaped 50 to receive a series of baskets extending the full length of the carrier.

A cylindrical screen 4^a is located within the carrier and forms the bottoms of the pockets 5. This screen is secured to the

heads 3 and the strips 4—making a light, yet substantial construction.

On each head 3 of the carrier are gear teeth, which mesh with the teeth of the gear wheels 6 on a shaft 7 that extends through one end of the casing. 8 is a worm wheel 60 on the shaft 7, which meshes with a worm 9 on a driving shaft 10, which is synchronized with the basket making machine.

The shaped strips and screen retain the baskets in the pockets while they are on the upper half of the carrier, and, as the pockets are open, a series of curved slats 11 are located directly under the lower half of the carrier so that, as the baskets pass the center, they rest upon the slats which hold them 70 in place while they are being carried to the delivery point α . As the slats are discontinued at this point, the nested baskets are released and slide down the incline 12 onto a belt conveyer 13, or other suitable receptacle.

In the present instance, the baskets are fed into the drier automatically.

14 is a belt conveyer, which receives the nested baskets in a damp condition from a basket making machine. Under the conveyer is a plate 15, which extends into the drying chamber close to the carrier. 16 is a pusher actuated from a timed shaft 17 through levers 18 and connecting rods 19 so 85 that a series of nested baskets will be in position to be projected into a pocket of the drier when the pocket is in proper alignment.

There is a considerable space between the 90 feeding mechanism and the discharge mechanism, as shown in Fig. 3. This space is closed by a curved plate 20.

21 are the heating coils located within the carrier 2. These coils are supported by I- 95 beams 22 extending longitudinally within the drier casing.

23 are the circulating fans. These fans are located in openings 24^a in stationary casings 34 within each end of the rotary 100 carrier and are mounted eccentrically in respect to the carrier so as to allow room for the coil supporting beams 22. Each fan is mounted on a shaft 25 extending to the outside of the casing and provided with a belt wheel. When the fans are in motion, the air circulates in the direction of the arrows, Fig. 1.

One of the baskets to be dried is illustrated in Fig. 4. These baskets are made of wood, or other suitable material and are bent into shape when in a damp condition. 5 The baskets are so designed that they can be nested—and one row after another is introduced automatically into the pockets of the carrier, and, as the carrier slowly rotates, the heated air in circulation dries the baskets so that, when they reach the delivery point α , they are in condition to be packed and shipped.

While the wheels 2^a are shown as supporting the carrier, it may be supported by bearings mounted on the beams 22, or it may be otherwise supported without departing from the main features of the invention.

We claim:

1. The combination in a drier, of a casing; a hollow rotary carrier arranged to rotate around a horizontal axis, said carrier having longitudinal pockets in its periphery to receive the articles to be dried; a series of heating pipes located within the rotary carrier but independent thereof; and means for circulating air within the casing and around the articles mounted on the carrier and around the heating pipes.

2. The combination in a drier, of a casing enclosing a drying chamber; a carrier located within the chamber, said carrier having two heads and L-shaped connecting strips forming pockets for the articles to be dried; means for circulating air in the drying chamber; and means for heating the air.

3. The combination in a drier, of a casing enclosing a drying chamber; a rotating carrier located within the chamber and having a series of pockets for the articles to be dried; a stationary casing at each end of the carrier, each casing having a fan opening; a circulating fan located in each fan

opening; means for operating the fans; and a heating coil supported within the carrier.

4. The combination in a drier, of a casing enclosing a drying chamber; a cylindrical carrier supported within the drying chamber having longitudinal pockets for the articles to be dried; an endless conveyer at one side of the drier; means for automatically transferring the articles to be dried from the conveyer to the pockets of the carrier; an endless conveyer under the first mentioned conveyer arranged to receive the articles as they are discharged from the carrier; and means for circulating heated air in the drying chamber.

5. The combination in a drier, of a casing enclosing a drying chamber; a cylindrical carrier located within the drying chamber, said carrier having a head at each end and strips extending from one head to the other so spaced as to form pockets for the articles to be dried; beams extending longitudinally through the carrier; heating coils mounted on the beams within the carrier; and a circulating fan at each end of the carrier mounted eccentrically in respect thereto.

6. The combination in a drier, of a casing enclosing a drying chamber and having a feed and a delivery opening; a cylindrical carrier located in the drying chamber, said carrier having a head at each end connected by a cylindrical screen and longitudinal strips, said strips being spaced apart to form pockets for the material to be dried; means for supporting the carrier; curved slats located directly under the carrier for supporting the articles as they are fed towards the discharge point; and means for circulating heated air in the drying chamber.

ELWOOD B. AYRES.
HERMANN BOGATY.
